UNITED STATES PATENT OFFICE.

EDWARD F. STODDARD AND EDWIN J. STODDARD, OF DECORAH, IOWA.

FARM-GATE.

1,058,487.

Specification of Letters Patent.

Patented Apr. 8, 1913.

Application filed May 7, 1912. Serial No. 695,674.

To all whom it may concern:

Be it known that we, EDWARD F. STODDARD and EDWIN J. STODDARD, citizens of the United States, residing at Decorah, in the county of Winneshiek and State of Iowa, have invented new and useful Improvements in Farm-Gates, of which the following is a specification.

This invention relates to farm gates, the object of the invention being to provide a gate of the class described which, when set, will slide to an open or shut position by the aid of gravity alone, and at the same time maintain the horizontality of the gate, either in an opened or closed position. Furthermore, the operating mechanism for the gate is adapted to be controlled at a suitable distance therefrom, to enable the same to be accomplished, without the necessity of the driver or rider dismounting.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a front elevation of the improved gate shown closed. Fig. 2 is a similar view, showing the gate opened. Fig. 3 is an elevation taken at right angles to Figs. 1 and 2, showing the operating mechanism. Fig. 4 is a detail section on an enlarged scale, showing the means for simultaneously elevating and depressing the track rails. Fig. 5 is a detail section taken at right angles to Fig. 4. Fig. 6 is a detail sectional view of the upper end of one of the end posts, showing the support for one of the track rails.

In the construction of the gate contemplated in this invention, we employ essentially a center post 1, and end posts 2 and 3 arranged at opposite sides of the center post and equi-distant or substantially so therefrom. The center post is located at one side of the roadway, while one of the end posts 2 is located at the opposite side of the roadway.

The supporting means for the gate consists of a pair of overhead track rails 4 and 5, the outer ends of which are supported and adapted to move longitudinally upon rollers 6 journaled in the upper ends of the end posts 2 and 3, while the inner ends of

said track rails 4 and 5 are pivotally connected to opposite ends of a cross head 7 mounted fast on a short shaft 8 journaled in bearings on the center post 1, 9 designating the pivots which connect the track rails 60 4 and 5 to the cross head.

On the same shaft 8 with the cross head 7 is a grooved pulley 10 adapted to receive a pair of operating ropes 11 which extend downwardly from the pulley 10 under guide 65 pulleys 12 secured to the center post, and thence upward over other guide pulleys 13 mounted on laterally extending horizontal arms 14 connected with the center post. The pulleys 13 are located at such a distance 70 from the center post and the plane of the gate that they may be conveniently grasped by the driver or rider, without the necessity of dismounting. It will be observed that when one of the ropes is pulled, the shaft 75 8 will be turned in one direction, and when the other rope is pulled, said shaft will be turned in the opposite direction. The effect of this is to alternately raise and lower the inner ends of the track rails 4 and 5, thereby reversing the inclination of the said track rails, for a purpose which will appear.

The gate which is hung entirely upon the track rails 4 and 5 comprises the end uprights 15 and 16 provided at their upper ends with rollers 17 which rest and travel upon the rails 4 and 5. In connection with the uprights 15 and 16, we employ any desired number of parallel rails or bars 18, each of which is connected at its opposite ends to the uprights 16 and 17 by a single bolt 19, which thereby forms a pivotal connection between the gate bars 18, and the end uprights, thus giving a parallel motion between the gate bars and uprights, so that the latter are always maintained in a vertical position by reason of their suspension from their upper ends on the track rails, hereinabove described.

From the foregoing description, it will 100 now be understood that by operating the ropes at opposite sides of the gate, the inner ends of the track rails may be correspondingly and simultaneously raised and lowered, so that both track rails 4 and 5 may be 105 inclined toward the roadway or away from the roadway. As soon as this adjustment of the track rails is effected, the gate will slide by gravity in one direction or the other in accordance with the angle to which the track 110

rails are set. Furthermore, the gate will remain in a perfectly horizontal position, whether opened or closed.

What is claimed is:

- 5 1. In a farm gate structure, the combination of a center post, two end posts equidistant therefrom, a cross head journaled on the center post, overhead track rails having their inner ends connected to opposite ends 10 of the cross head and their outer ends slidably supported on the end posts, a gate having end uprights provided with rollers to travel on said rails, and operating means for turning said cross head.
- 15 2. In a farm gate structure, the combination of a center post, two end posts equidistant therefrom, a cross head journaled on the center post, overhead track rails having their inner ends connected to opposite ends 20 of the cross head and their outer ends slidably supported on the end posts, a gate having end uprights provided with rollers to

travel on said rails, and operating means for turning said cross head, embodying ropes connected with said cross head.

25

3. In a farm gate structure, the combination of a center post, two end posts equidistant therefrom, a cross head journaled on the center post, overhead track rails having their inner ends connected to opposite ends 30 of the cross head and their outer ends slidably supported on the end posts, a gate having end uprights provided with rollers to travel on said rails, and operating means for turning said cross head, embodying a pulley 35 fast on the shaft of the cross head and ropes connected to said pulley.

In testimony whereof we affix our signatures in presence of two witnesses.

EDWARD F. STODDARD.
EDWIN J. STODDARD.
